HEEL AND ARCH SUPPORT

Harry H. Ahern, Newport News, Va.

Application January 23, 1936, Serial No. 60,514

6 Claims. (Cl. 36—71)

This invention relates to a heel and arch support, and it is primarily an object of the invention to provide a device of this kind comprising a supporting member to be placed within a shoe, 5 said member being of a length to permit effective coaction with the arch and heel of the foot upon which the shoe is applied, said supporting member being provided with means to adjustably hold to the supporting member one or more pads of 10 any desired material to facilitate the building up of the foot as may be required or for lifting or elevating the heel as the condition of the foot may require.

Another object of the invention is to provide a 15 device of this kind including a supporting member for insertion within a shoe and which member carries one or more pads readily adjusted to selective positions upon the supporting member as may be required by the condition of the metatarsal and/or tarsal bones to build up the foot to restore both the longitudinal and lateral arches of the normal foot structure, or said pad or pads may be selectively adjusted with respect to the 20 os calcis to effect an adjustment as may be required by the tibia or fibula to raise or elevate the heel to correct any tendency of the heel to turn.

An additional object of the invention is to provide a device of this kind which may be readily 25 and conveniently adjusted or regulated to provide simultaneous support to the foot in proper proportion to the amount of support needed and which is therefore useful in relieving pain and also substantially eliminating or reducing to a 30 minimum the formation of bunions, callouses, hardened skin and kindred elements.

The invention consists in the details of construction and in the combination and arrangement of the several parts of my improved heel 35 and arch support whereby certain important advantages are attained and the device rendered simpler, less expensive and otherwise more convenient and advantageous for use, as will be hereinafter more fully set forth.

40 The novel features of my invention will hereinafter be definitely claimed.

In order that my invention may be the better understood, I will now proceed to describe the 45 same with reference to the accompanying drawing, wherein:—

Figure 1 is a view in perspective of a heel and arch support constructed in accordance with an embodiment of my invention and in an inverted 50 position;

Figure 2 is a view in bottom plan of the device as illustrated in Figure 1;

Figure 3 is a longitudinal sectional view taken substantially on the line 3—3 of Figure 2 with the device in proper position;

Figure 4 is a sectional view taken substantially on the line 4—4 of Figure 2.

As disclosed in the accompanying drawing, S denotes a foot supporting member in its entirety and which, as herein disclosed, comprises a relatively thin plate 1 having its marginal portion returned to provide a marginal bead or flange 2 whereby said marginal portion of the plate 1 is effectively reinforced to assure the maintenance of the plate 1 in desired formation. I do not, 15 however, wish to limit myself to the foot supporting member being made of only one plate because if preferred a plurality of superimposed plates may be employed and arranged as is, for example, comprised in my prior Patents #1,701,252 of February 5, 1929 and #1,858,178 of May 10, 1932.

In the present instance the plate 1 has a rear depression 3 for the reception of the heel of the foot which, as is well known, in the normal foot protrudes lower than the arch and instep of the 25 foot. The plate 1 is also formed with the convex portion 4 forming a rest or support for the arch of the foot and this convex portion 4 is continued by a somewhat flattened portion 5 which extends slightly downward to facilitate the insertion or 30 withdrawal of the foot, and particularly with an applied stocking, within the shoe in which the device is arranged.

The forward part of the flattened portion 5, as herein disclosed, is provided with a convex portion 35 6 to assure adequate support for the phalanges of the foot although when circumstances warrant this portion 6 may be dispensed with.

The particular formation of the plate 1 as hereinbefore referred to forms no part of the 40 present invention as this plate as disclosed in the accompanying drawing forms no part of the present invention as this plate as disclosed in the drawing is substantially the same in contour and formation as the foot support described and 45 illustrated in my already issued Patent #1,858,178 hereinbefore referred to.

To the outer side of the plate 1 closely adjacent to but slightly to the rear of the portion 6 and to one side of the transverse center of the plate 1 50 is pivotally connected, as at 7, a plurality of elongated arms 8, 9 and 10. Each of these arms is of tempered steel or other material whereby the arm possesses a certain degree of inherent resiliency. While I am showing three of these arms 55

in the present embodiment of my invention, I wish to state at this time that the number may be increased or decreased as the individual circumstances may make the most desirable. Associated with each of these arms 8, 9 and 10 are the pads 11 herein disclosed as circular or disk-like in form although I do not wish to limit myself to this particular design. The central portion of each of these pads 11 is provided with a pair of spaced slots 12 through which threads one of the three arms 8, 9 or 10. By this means the pad 11 may be readily applied or removed and when in applied position may be adjusted along its arm to best suit the requirements of practice and particularly to permit of a selective adjustment of the pad with respect to the metatarsal, the tarsal bones or the os calcis.

It is also to be noted that the arms 8, 9 and 10 are of differing lengths. This is of importance and advantage as it permits the adjustment of the pad over a greater area of the plate 1. The longest arm 8 is of especial advantage in adjusting the pad 11 toward the forward end of the plate while the shorter arms 9 and 10 can be employed to advantage in adjusting the pad either laterally of the plate 1 or in a direction toward the heel end.

In addition to the adjustment of the pad 11 along its arm it is to be noted that a further adjustment of each of the pads with respect to the plate 1 or the sole of the foot may be obtained by swinging the arms about its pivot.

It is also to be stated that the inherent resiliency of each of the arms 8, 9 and 10 is such as to maintain the central portion of the pad 11 in close and firm frictional contact with the adjacent or under surface of the plate 1 so that each of the pads will be effectively maintained in its desired adjusted position during the use of the device.

40 The pads 11 may be of any material desired such as rubber, rubber compound, metal, leather, or fiber.

The bead or flange 2 hereinbefore referred to in addition to reinforcing the marginal portion 45 of the plate 1 also provides a finished edge for the plate which will not catch in the lining of the shoe as the device is applied or removed from the shoe. This flange or bead also provides a marginal edge which will not cut into the foot being 50 supported or become entangled with the stocking on said foot.

From the foregoing description it is thought to be obvious that a heel and arch support constructed in accordance with my invention is par-

ticularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter 10 claimed.

I claim:—

1. A heel and arch support comprising a plate to be positioned at the heel and instep portion of a shoe, an arm pivoted to the plate, and a pad 15 mounted upon the arm for sliding movement lengthwise thereof.

2. A heel and arch support comprising a plate to be positioned at the heel and instep portion of a shoe, an arm pivoted to the plate, and a pad 20 mounted upon the arm for sliding movement lengthwise thereof, said arm possessing inherent resiliency for coaction with the plate to frictionally hold the arm and pad in selected adjustments.

25 3. A heel and arch support comprising a plate to be positioned at the heel and instep portion of a shoe, an arm pivotally connected to the plate, a pad, the central portion of the pad having spaced slots, the arm threading through the slots 30 whereby the pad is connected to the arm for sliding movement in either direction along the arm.

4. A heel and arch support comprising a plate to be positioned at the heel and instep portion of a shoe, a plurality of elongated arms, a common 35 pivot for the arms for holding said arms to the plate for swinging movement, and a pad slidably engaged with each of the arms.

5. A heel and arch support comprising a plate to be positioned at the heel and instep portion 40 of a shoe, a plurality of elongated arms, a common pivot for the arms for holding said arms to the plate for swinging movement, and a pad slidably engaged with each of the arms, one of said arms being of a length greater than the 45 remainder.

6. A heel and arch support comprising a plate to be positioned at the heel and instep portion of a shoe, an arm pivoted to the forward portion of the plate to one side of the transverse center of 50 the plate, and a pad mounted upon the arms for sliding movement lengthwise thereof.

HARRY H. AHERN.
